CLAIM

The ornamental design for a sorter for a copying machine, as shown and described.

DESCRIPTION

FIG. 1 is a front, top and right side perspective view of a sorter for a copying machine showing our new design; FIG. 2 is a front elevational view thereof; FIG. 3 is a top plan view thereof; FIG. 4 is a rear elevational view thereof; FIG. 5 is a bottom plan view thereof; FIG. 6 is a left side elevational view thereof; FIG. 7 is a right side elevational view thereof; and, FIG. 8 is a perspective view thereof, the broken line showing of a copying machine is environmental only and forms no part of the claimed design.

Fig. 1
